W. N. TAYLOR

AMUSEMENT DEVICE

Filed Oct. 27, 1923

INVENTOR:

William N. Taylor,

BY *Arthur D. Gould,*

ATTORNEY.

UNITED STATES PATENT OFFICE.

WILLIAM N. TAYLOR, OF CINCINNATI, OHIO.

AMUSEMENT DEVICE.

Application filed October 27, 1923. Serial No. 671,246.

To all whom it may concern:

Be it known that I, WILLIAM N. TAYLOR, a citizen of the United States, and resident of Cincinnati, in the county of Hamilton and State of Ohio, have invented a certain new and useful Amusement Device, of which the following is a full, clear, and exact description, reference being had to the accompanying drawings, forming a part of this specification.

My invention relates to amusement devices, and especially to the provision of an amusement device in the nature of a mathematical puzzle.

The object of this invention is to provide a puzzle of entertaining as well as educational value.

In the drawings:—

Figure 1 is a perspective of the board with one of the counters in place;

Figure 2 is a perspective of one of the counters;

Figure 3 is a plan view of the device with the counters in position.

The numeral 1 indicates a board which may be either of wood, metal, cardboard or other suitable material. As shown in the drawings the board 1 is square in shape but the same may be varied to suit individual preference or manufacturing expediency.

The board 1 is provided with a series of perforations arranged preferably in radial relation from a central perforation 2, the radiating perforations being arranged in series of three each, and the series being designated in the drawings by the numerals 3, 4, 5, 6, and 7, respectively.

In connection with the board 1, a series of 16 counters is provided, each of the counters being provided with a substantially spherical body portion 8, adapted to fit in either of the perforations in the board, and a face 9 on which appears a numeral 10, the counters being numbered from 1 to 16 both inclusive.

In place of the board 1 being provided with perforations it will be understood that the same may be provided merely with

marked spaces or pins, in which event the counters would be correspondingly altered so as to be used in connection therewith.

The board and counters constructed as above set forth, are to be used in the following manner:—

The object of the game or puzzle is to arrange the counters in five series in the perforations with the numbers exposed, so that each of the series, including the middle perforation 2 as a number of each series, will total the same. As an element of the operation of the puzzle it is to be understood that the counters may be placed in a number of different arrangements so as to make series having a common total.

Having thus fully described my invention what I claim as new, and desire to secure by Letters Patent, is:—

1. An amusement device comprising a board, said board being provided with a plurality of equal series of spaces radiating from a central space, counters equal in number to the spaces on said board, each of said counters being provided with a numeral in arithmetical progression.

2. An amusement device comprising a board, said board being provided with a plurality of equal series of perforations radiating from a central perforation, counters equal in number to the perforations on said board, each of said counters being provided with a body arranged to fit into any of said perforations, and a face containing a numeral, the numerals on the counters being arranged in arithmetical progression.

3. An amusement device comprising a board, said board being provided with a plurality of equal series of perforations radiating from a central perforation, spherical counters equal in number to the perforations on said board, each of said counters being provided with a flat face upon which one of a series of numbers in arithmetical progression equal in number to the perforations in said board is displayed.

WILLIAM N. TAYLOR.
